[57] CLAIM

The ornamental design for a bowl-colander set, as shown and described.

DESCRIPTION

FIG. 1 is a top view of a bowl-colander set according to the present invention.

FIG. 2 is a front view of the bowl-colander set shown in FIG. 1.

FIG. 3 is a left side view of the bowl-colander set shown in FIGS. 1 and 2.

FIG. 4 is a bottom view of the bowl-colander set shown in FIGS. 1-3.

FIG. 5 is a right side view of the bowl-colander set shown in FIGS. 1-4.

FIG. 6 is a top view of the bowl-colander set with the colander inverted onto the bowl.

FIG. 7 is a front view of the bowl-colander set as shown in FIG. 6, with the colander inverted atop the bowl; and,

FIG. 8 is a left side view of the bowl-colander set as shown in FIGS. 6 and 7 with the colander atop the bowl.
